George Schrade Inventor:

By his Attorney W. L. Malcomson

UNITED STATES PATENT OFFICE.

GEORGE SCHRADE, OF BRIDGEPORT, CONNECTICUT.

ROUTING MACHINE.

Application filed May 5, 1927. Serial No. 189,018.

This invention relates to machines used for routing out space for inlaying work and more especially to that class of such machines adapted to work on a thin piece of bone, ivory, wood or similar substance such as is used for the covering of the handles of pocket knives, where it is required to produce a recess in said coverings for the inlay of a name plate or shield.

10 My present improvements embody new and improved mechanism for holding and operating the work and dies in combination with the chisels for routing out the material in making the required plate recess. The 15 chisels used and the means for operation of such chisels are described in Letters Patent heretofore obtained by me, numbered 985, 117.

The present improvements relate particularly to the die and its appurtenances for routing the space in the material operated upon and also the means for receiving and holding said die in its place.

In the accompanying drawings Fig. 1 represents a side elevation of the entire routing machine with my improvements; Fig. 2 shows a left hand side view of Fig. 1.

Fig. 3 indicates an enlarged section of Fig. 1, on the line 3, 3;

30 Fig. 4 represents a section of Fig. 3 on the line 4, 4;

Fig. 5 shows a bottom plan view of the die plate holder;

Fig. 6 indicates a left hand side view of Fig. 5;

Fig. 7 represents a top plan view of the die plate;

Fig. 8 is a side view of Fig. 7;

Fig. 9 shows a top plan view of the work 40 or side cover to be operated upon;

Fig. 10 is a section of Fig. 9 on the line 10, 10; and

Fig. 11 indicates a perspective view of the plate which is to be inserted in the said 45 cover.

The routing machine comprises a pedestal, 1, of any desired height and available construction, which has on its face the guide ways 2, and at its head a bracket 3 for the shaft 4 of the driving pulley 5.

Above the pedestal 1 and secured thereto is an upright extension 6. Above the extension 6 and secured thereto is an outwardly extending bracket 8, which terminates in a

journal bearing 10 and an upright extension 55 bent at the top to provide a journal 9 for the upper end of the spiral shaft. The extension 6, at its top is also provided with a fulcrum 11, in which is pivoted a link 12, to support the driver or walking beam 13, having the 60 forked end 13' and which is actuated by means of the crank arm 14 on the shaft 4 through the connecting link 15.

The forked end 13' has pivoted therein a nut, not shown, through which plays, when the walking beam 13, is actuated, a driving spiral shaft 17, the journal ends of which are journaled in the bearings 9 and 10. At the lower end of the spiral shaft 17 is an adjustable collar 18, which is secured to the 70 spiral shaft and forms a surface to support the same on the bearing 10. A clamping lug 21, having the shank 21^a and the heel 22 is detachably connected to the head 20 and is provided with openings for the clamping 75 screws 23. A tool holder 24, has formed therewith a pair of openings 25, 26 for the upper ends of routing tools 27, one of which only is shown. The screws 28, detachably clamp the upper ends of the routing tools to 80 the holder 24. When the walking beam 13 oscillates, the spiral shaft 17, is rotated first in one direction and then in the reverse direction.

When the narrowest part of the mortise 85 that is being cut in the material operated upon, is reached the two tools, if two are used, will be brought together by the opening in the die plate, and the spring action of the metal of which the long tools are 90 made will cause them to spring outwardly whenever the opening in the die permits of such action. It is available to use either one or two routing tools as the shape or size of the mortise to be cut requires. I prefer to 95 use only one tool or bit for the greater portion of the work. It must be understood that in speaking of the routing chisels the work tool, or tools, are used to designate substantially the same thing, two chisels 100 making up the routing tool when the style or size of the space in the die permits.

In the face 6' of the extension 6 is fastened the rack plate 29 having the rack teeth 29^a. Dovetail guides 30 are formed on the 105 opposite sides of the base 6'. A movable frame 31 is indicated with the head 32. A vertical guide slot having the beveled end 33

and straight end 33^a, is formed in the frame 31. A second vertical guide slot having the beveled ends 34 and 34^a is also formed in the frame 31. A gib 35 is located between the straight end 33^a, and its accompanying dovetail guide 30. A pair of bolts 36 of which only one is shown extend through the gib 35 and are in threaded engagement with the frame 31. A screw 37 has fastened thereto a socket 37^a having the handle 37^b. The screw 37 is in threaded engagement with the frame 31 and bears against the gib 35 to properly adjust the latter and maintains the frame 31 in proper position. A cavity 38 is formed in the head 32, and a pinion 39 is located in said cavity. A shaft 40 having the shank 41 of a small diameter is journaled in the head 32. A key 42 fastens the said pinion to the shank 41. An operating hand wheel 43 is fastened to the shaft 40. The pinion 39 meshes with the rack teeth 29^a. By means of the said pinion and its appurtenances the frame 31 can be located at different levels, and by means of the handle 37^b said frame can be locked in operative position.

A movable slide is indicated with the leg 44, having the longitudinal dovetail sides 44^a and 44^b. The said bracket has one side bearing against the end 34 of the vertical guide slot and its other side against the gib 44^c, which latter in turn bears against the beveled end 34^a. Screws 44^d, only one of which is shown, bear against the gib 44^c. A pin 45 extends from the frame 31 and enters a guide opening 46 in the leg 44. A foot 47 is formed with the leg 44. A projecting arm 48 is detachably fastened to the top face of the head 32, by means of the screws 49. An adjusting screw 50 is in threaded engagement with the arm 48 and a jam nut 51 is provided for the screw 50, which latter is adapted to bear on the top face of the leg 44, to vertically adjust the latter relatively to frame 31. By means of the screws 44^d the leg 44 can be adjusted so it will slide freely vertically without lost motion.

A die plate holder is indicated in its entirety by the body portion 53 having the elongated opening 54. A thickened end 55 having the beveled inner locking edge 56 is formed with the body portion 53. A bolt opening 57 is formed in the thickened end as shown at 58, and has formed therewith the spring member 59 having the beveled inner locking edge 60. A bolt opening 61 is formed in the thickened portion 58. The inner face 52^b and the inclined locking edges 56 and 60 constitute a seat for the die plate to be described. The die plate holder 52 is detachably fastened to the foot 47 by means of bolts 61^a, and 61^b, the face 52^b of the die holder bears against the under face of said foot 47.

Secured to the guide way 2 of the pedestal 1 is a sliding block 65, which can be clamped in different positions by means of the set screw 66. A rack bar 68 is slidably guided in the block 65 and has the table 69 at its upper end. A block 70 is fastened to the table 69 by means of the bolts 71. A work holder 72 is pivoted to the block 70 by means of the pivot 73. The work holder 72 is recessed on its upper face for the plates 78 which are clamped in position by means of the bolts 79. Holding pins 80 extend upwardly from the plates 78 and are intended to fit into holes in the covers to be described. By means of this construction the work holder 72 is enabled to tilt to adjust itself to inequalities of the covers. The plates 78 are slotted for the passage of the bolts 79, to permit adjustment. The work holder 72 can rock or tilt for the purpose of allowing a small degree of freedom of movement for the inequalities in the thickness along the length of the covers operated upon, so the bottom of the cavity will be parallel to the top of the covers. The die plate is indicated at 82 with the beveled ends 83 and the die opening 85. The cover to be operated upon is indicated at 86 with the openings 87, and the recessed cavity 88, which has been made by the routing tools 27 through the opening 85 of the die plate 82.

A shaft 90 is journaled in the block 65. A handle 91 is fastened to one end of the shaft 90 and to its other end is fastened the crank arm 92. The pinion 93 which meshes with the teeth of the rack bar 68, is fastened to the shaft 90 in order to raise and lower the work holder 72 with its appurtenances. The crank arm 92 has extending from its inner face a stud 96. The latter plays in a recess 97 of a slide bar 98 supported in a box 99.

A bracket 100 extends from the block 65 and has pivoted thereon the bell crank lever 101 which has a forked end (not shown) that fits a pin (not shown) carried by the bar 98. The other arm 102 of the bell crank lever actuates the bell shifter 103 which slides on the pin 104 that extends from the pedestal 1. When the work holder is elevated by means of the handle 91, the belt 105 is thereby shifted from the loose pulley 106 to the tight pulley 107, as fully described in my Patent No. 985117 and the operations of routing immediately begin but only continue as long as the work holder 72 is elevated and the tool or tools are working upon the cover 86. Simultaneously with the dropping of the work holder the belt is automatically shifted to the loose pulley 106 and the routing tool 27 comes to a rest.

To locate the die plate 82 in the die plate holder 52 it is pushed between the locking edges 56 and 60. The die plate 82 is then

seated in the die plate holder, 61^a and 61^b. By this means the spring member 59 is brought together and the die plate 82 is tightly clamped in place. The cover 86 is next located upon the plates 78, Fig. 2, with its openings 87 engaged by the pins 80.

The plate 110, for the knife cover preferably having the openings 111 may be then readily located in the routed cavity 88 and fastened in place by cement or by pins extending from the cover 86.

It will be observed that in my new construction the die plate holder, 52, and its appurtenances are held fixedly attached to the sliding frame 31 whilst the dies may be readily removed by loosening the nuts on the screws 61^a and 61^b and other dies for the routing of various shapes substituted.

I claim:

1. In a machine of the class described a routing tool rotatively supported therein, a movable frame slidably supported in the machine, a die plate holder carried by said frame, said holder having a spring member 20 to clamp a die plate thereto and means for securing the die plate in the holder substantially as shown and described.

2. In a machine of the class described the combination of a routing tool rotatively supported therein, means to rotate the routing tool in reversed directions, a movable frame slidably supported in the machine, a die plate holder carried by said frame, said holder having a retaining spring member, a die plate adapted to be locked to said holder, means to fasten said die plate holder to said frame, said means simultaneously clamping said die plate to said holder.

3. In a machine of the class described the combination of a routing tool supported therein, means to rotate the routing tool in reversed directions, a die plate holder having an opening, fastened in the machine and disposed so that the routing tool extends through its opening, said die plate holder having a locking edge at one portion thereof, and having a thickened end spaced from said locking edge, a spring member formed with said thickened end, said spring member having a beveled locking edge and a die plate having a work opening, adapted to be detachably clamped to said holder, substantially as and for the purpose shown and described.

4. In a machine of the class described the combination of a routing tool, means to rotate said tool in reversed directions, a die plate holder having an opening for the passage of the routing tool detachably supported in the machine, said die plate holder having a beveled locking edge at one portion thereof, a spring member having a beveled locking edge formed with the die plate holder, and spaced from the other locking edge, a die plate having beveled edges and a work

opening for said holder, with its beveled edges adapted to engage the locking edges of the holder, substantially as and for the purposes shown and described.

5. In a machine of the class described the combination of an extension supported therein, a movable frame in slidable relation to said extension, means to clamp the frame at different levels to said extension, a bracket in slidable relation to said movable frame, means to adjust said bracket in different positions, means to clamp said bracket to said frame and a die plate holder detachably connected to said bracket, substantially as and for the purposes shown and described.

6. In a machine of the class described the combination of an extension supported therein, a movable frame in slidable relation to said extension, a rack plate connected to said extension, a pinion journaled to said frame and in mesh with the teeth of said rack plate, means to clamp the frame at different levels to said extension, a bracket slidably connected to said frame, an adjusting screw extending from said frame and adapted to bear against said bracket to adjust the latter relatively to said frame and a die plate holder detachably connected to the frame.

7. In a machine of the class described the combination of an extension supported therein, a movable frame in slidable relation to said extension a rack plate connected to said extension, a pinion journaled to said frame in mesh with the teeth of the rack plate, means to turn the pinion, a gib interposed between the frame and extension, means to clamp the frame, the gib and extension together, a bracket in slidable relation to said frame and an adjusting screw extending from said frame and adapted to adjust the bracket in different positions, substantially as and for the purposes shown and described.

8. In a machine of the class described the combination of an extension supported therein, a movable frame in slidable relation to said extension, a rack plate connected to said extension, a pinion journaled to said frame in mesh with the teeth of the rack plate, means to turn said pinion and thereby run the frame in reversed directions, means to clamp the said frame in different positions, a bracket in slidable relation to said frame, means to clamp the bracket in different positions, a die plate holder detachably connected to the bracket, a die plate detachably secured to said holder and a work holder in movable relation to said die plate holder, substantially as and for the purposes shown and described.

9. In a machine of the class described the combination of an extension supported therein, a movable frame in slidable rela-

tion to said extension, a rack plate connected to said extension, a pinion journaled to said frame in mesh with the teeth of the rack plate, means to turn the pinion and thereby run the frame in reversed directions, means to clamp the frame in different positions, a bracket in slidable relation to said frame, free to adjust itself in accordance with the work in different positions by gravity a die plate holder detachably connected to the bracket a die plate detachably secured to said holder and, a work holder in movable relation to said die plate holder.

GEORGE SCHRADER.
